PORTABLE BATTERY CHARGER

Eugene B. Raymond, 4041 Grove St., Skokie, Ill. 60076

Filed Sept. 7, 1965, Ser. No. 86,878

Term of patent 3½ years

(Cl. D26—15)

Fig. 1.

Fig. 2.

Fig. 3.

FIG. 1 is a perspective view of a portable battery charger showing my new design, the opposite side being substantially the same, and the back being substantially plain;

FIG. 2 is a bottom plan view thereof;

FIG. 3 is a sectional view of the casing thereof, taken on line 3—3 of FIG. 2.

The broken line showing of legible matter is for illustrative purposes only. A portion of FIG. 1 is diagonally lined to indicate transparency.

I claim:

The ornamental design for a portable battery charger, as shown and described.
